UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed May 17, 1921. Serial No. 470,335.

To all whom it may concern:

Be it known that I, EPPA H. RYON, a citizen of the United States, residing at Waltham, in the county of Middlesex and State of Massachusetts, have invented a new and useful Weft-Detecting Mechanism, of which the following is a specification.

This invention relates to weft detecting mechanism used to indicate weft exhaustion in an automatic loom and particularly concerns changes and improvements in detecting mechanism using multiple detecting elements, as shown in my prior Patent No. 1,221,768 issued April 3, 1917.

It is an important object of my invention to provide a construction by which detecting mechanism of this type may be used to indicate a weft carrier transfer to be completed on the same beat of the lay in which weft exhaustion is detected.

Another object is to provide a detecting mechanism for use in connection with transfer mechanism of the type shown in my prior Patent No. 1,032,709 issued July 16, 1912, but in which the actuating parts are normally maintained in inoperative relation.

With these and other objects in view my invention consists in certain arrangements and combinations of parts which will be hereinafter described and more particularly pointed out in the appended claims.

A preferred form of my invention is shown in the drawings in which

Fig. 1 is a side elevation of my improved detecting mechanism;

Fig. 2 is a partial side elevation showing certain of the parts in a different position;

Fig. 3 is a rear elevation of the detecting mechanism;

Fig. 4 is a front elevation thereof, and

Fig. 5 is a detail view of certain parts shown in Fig. 3 but in a different position.

Referring to the drawings, I have shown portions of a loom frame 10 supporting a stud 11 upon which is mounted a transferrer 12. A bracket 13 is also secured to the loom frame and supports a casting or stand 14 upon which the several parts of the detecting mechanism are supported. An L-shaped plunger 15 is mounted to slide vertically in guideways in the stand 14 and is regularly reciprocated by a link 16 which receives motion from any suitable driving

mechanism, not shown. One form of such driving mechanism is clearly disclosed in my prior Patent No. 1,032,709 previously mentioned.

The upper end of the plunger 15 is formed as a hook 17 (Fig. 1) where it is adapted to engage a hook 18 pivoted at 19 on the transerrer 12. A bolt 20 extends through an upward extension 21 of the hook 18 and also through a lug 22 on the transerrer 12 and limits movement of the hook 18 away from the hook 17. A spring 23 on the bolt 20 yieldingly maintains the hook 18 in the position shown in Fig. 1.

A rod 24 (Fig. 3) is also mounted to slide vertically in the stand 14 and downward movement thereof is limited by the engagement of the lug 25 on the plunger with an adjustable stop screw 26 threaded into a projection on the stand 14. A spring 27 surrounds the rod 24 and is positioned between a lower surface of the stand 14 and a washer 28 secured on the rod by a pin 29.

A lifting stud 30 (Fig. 1) is adjustably secured in the horizontal extension 31 of the plunger 15 and engages the rod 24 as the plunger 15 moves upward, the parts being again separated as the plunger moves downward as clearly shown in Fig. 5.

An arm 32 (Fig. 2) is pivoted at 33 to the upper end of the rod 24 and is provided with an adjustable contact screw 34 positioned to engage the hook 18. A projection 35 extends laterally from the arm 32 and a portion thereof engages a shoulder 36 on the head of the rod 24 which thus forms a stop for the arm 32.

The weft engaging mechanism shown herein comprises a series of detecting members 37 (Fig. 1) each preferably comprising a single U-shaped piece of wire slidably mounted in a holder 38. The holder 38 has a head portion 39 in which is formed a groove or notch 40 (Fig. 1) fitting a horizontal projection 41 on the stand 14. A bolt 42 extends loosely through the head 39 and stand 14 and a spring 43 on the bolt retains the holder yieldingly in position on the stand.

The detecting members are normally maintained in their rearward or operative position by a spring plate 44 (Fig. 4) fixed to a block 45 loosely pivoted on a stud 46 which is secured in a projection 47 of the stand 14 by a set screw 48. A light spring 110

49 is coiled around a reduced hub portion of the block 45 and one end thereof is secured to a cross pin 50 fixed in the stud 46. The other end of the spring is secured to the block 45. The effect of the spring may be easily adjusted by loosening the set screw 48 and turning the stud 46 to increase or decrease the tension of the spring.

When the detecting members are in their rearward or operative position, the lower and shorter legs of the detecting members extend into the path of the projection 35 on the arm 32, as shown in Fig. 2. When engaged by a weft carrier having a sufficient supply of weft thereon, the detecting members are moved forward thereby out of the path of the projection 35.

The mechanism is commonly used with weft carriers or bobbins having a plurality of transverse holes therein, as shown in my prior Patent No. 1,220,685 issued March 27, 1917. Some one of the weft detecting members 37 will enter a hole in the bobbin as soon as it is uncovered by substantial exhaustion of the weft covering the same and will remain in such rearward or operative position for engagement by the projection 35 as the rod 24 descends. This engagement causes a swinging movement of the arm 32 which advances the hook 18 into the path of the hook by which the transferrer is thereupon operated to insert a fresh weft carrier in the shuttle.

It is essential that all of the detecting members 37 should be withdrawn during the transfer operation and for this purpose I provide a bell crank 51 (Fig. 1) also pivoted on the stud 46 and having a pin 52 extending behind the upright portions of the detecting members 37. The transferrer 12 is provided with a depending arm 53 having a stud 54 which engages the bell crank 51 as the transferrer moves downward and swings the bell crank to withdraw the members 37 from their rearmost or operative position so that they will not be engaged by the fresh weft carrier as it enters the shuttle.

The bell crank 51 may also be conveniently grasped by the loom operator whenever it is desired to temporarily prevent operation of the detecting mechanism as, for instance, upon starting a loom after the insertion of a new warp.

Having thus described my invention and the operation thereof it will be evident that changes and modifications can be made therein by those skilled in the art within the spirit and scope of my invention as set forth in the claims, and I do not wish to be other-

wise limited to the details herein disclosed but what I claim is:—

1. In a loom, in combination, a transferrer, an actuating device therefor having a regularly repeated operative movement, a normally inoperative connector between said transferrer and said operative device, and means to move said connector to operative position upon indication of substantial exhaustion of weft on the active weft carrier. 65 70

2. In a loom, in combination, a transferrer, an actuating device therefor having a regularly repeated operative movement, a normally inoperative connector between said transferrer and said operative device, a positioning device for said connector also having regularly repeated operative movements, and a weft detecting element effective to cause additional movement of said positioning device to advance said connector to operative position upon substantial exhaustion of weft on the active weft carrier. 75 80

3. In a loom, in combination, a trans- 85 ferrer, a regularly actuated plunger having a hooked upper end, a hook pivoted to said transferrer for engagement by said plunger, a rod movable by said plunger, an arm pivoted thereto and engaging said hook, said arm having a projection, and a detecting member normally positioned in the path of said projection but movable from such position by engagement with a weft carrier having a sufficient supply of 90 95 weft thereon.

4. In a loom, a plurality of weft detecting elements, a spring plate yieldingly holding all of said elements in operative position, a transferrer having a depending arm and a lever movable by said arm and having a pin directly engaging all of said detecting elements and effective to withdraw said elements from operative position when the transferrer is actuated. 100 105

5. Weft detecting mechanism comprising a holder, a plurality of weft detecting elements slideable in said holder, said elements being each formed from a single U-shaped piece of wire with legs of unequal length, 110 means to indicate transfer upon engagement of said means by the end of the shorter leg of any one of said elements, and means directly engaging all of said elements and effective to slide said elements 115 forward in said holder out of operative position during weft carrier transfer.

In testimony whereof I have hereunto affixed my signature.

EPPA H. RYON.
